UNITED STATES PATENT OFFICE.

EDOUARD ALEXIS VIVINUS AND AUGUST JULES HECHT, OF SCHAERBEEK, BELGIUM.

OIL-CONTAINER FOR MOTORS.

SPECIFICATION forming part of Letters Patent No. 638,190, dated November 28, 1899.

Application filed August 1, 1899. Serial No. 725,767. (No model.)

To all whom it may concern:

Be it known that we, EDOUARD ALEXIS VIVINUS, a citizen of the French Republic, and AUGUST JULES HECHT, a subject of the Empire of Germany, both residing at Schaerbeek-lez-Brussels, Belgium, have invented Improvements in and Relating to Oil-Containers for Motors, of which the following is a specification.

- 10 This invention relates to an oil-container for motors, especially explosion-motors, so formed and arranged that an abundant lubrication of the working parts and of the cylinder of the motor is obtained, the oil is protected from dust and circulation of air from the outside to the inside of the container, and, vice versa, permitted so that the necessary cooling of the said parts and of the interior of the cylinder is brought about.
- 20 According to our invention the container is fixed to the open end of the cylinder, covers the moving parts, and forms an oil-bath, the said receptacle being furnished with laterally-arranged outlets, each closed by one or more sheets of wire-gauze or perforated metal plates which prevent the oil from being projected outward and the entry of dust, but allow of the aspiration of fresh air and the expiration of the air heated by contact
- 30 with the inclosed parts of the motor.

In the accompanying drawings, Figure 1 is a vertical section of an oil-container constructed in accordance with this invention and applied to a vertical motor, and Fig. 2 is a vertical section at right angles to Fig. 1.

The container comprises a box-like structure *c*, which forms at the same time the base of the motor.

The container is fixed at its upper end to the lower end of the cylinder *d*, in which the piston *e* reciprocates.

The sides of the container are formed by cheeks *h k*, Fig. 2, one of which is furnished with the bearing *i* for the end of the crank-shaft carrying the fly-wheel and the other with the bearing *j* for the end of the shaft which actuates the valves. The cheeks *h k* may be cast in one with the rest of the container *c*, or the container may be made in

50 two parts or halves, each of which constitutes

a cheek, a joint being thus formed in the middle of the container.

On the sides of the container are arranged two channels or passages *a a*, rising upward, preferably inclined and each closed at each end by a sheet of wire-gauze or a perforated metal plate *b*.

The lower part of the container is filled with oil up to a point *g*—that is to say, to a sufficient level for the crank and crank-pin 60 actuated by the connecting-rod *f* to plunge into the oil. This level is kept constant by a suitable feed and overflow tube. (Not shown.) During working the connecting-rod and crank dip into the oil at each revolution. 65 When the motor works normally, this oil is projected by the moving parts in all directions, resulting in an abundant lubrication.

The sheets of wire-gauze or perforated metal plates *b* prevent the oil from being projected outside through the passages or conduits *a a*, the sheets placed at the lower end stopping the passage of jets of oil or breaking them up, so that they cannot dash violently against the sheets at the upper end and flow 75 out. The small amount of oil which may get past the first sheets is led back to the container owing to the inclination of the sides of the openings or conduits *a a*. These sheets, while at the same time preventing dust from 80 penetrating into the interior of the container, allow air to be drawn in toward the interior of the container and to be expelled therefrom after having cooled parts of the motor, such as the connecting-rod, piston, and the interior of the cylinder. 85

What we claim is—

1. An oil-container for motors comprising a main body portion adapted to receive the crank and pitman of the motor and constructed to receive oil, laterally-extending inclined passages leading into the said body portion, perforated screens or plates mounted in each end of the said passages, whereby two screens will be interposed between the outer air and the interior of the oil-container in each passage-way for permitting an inflow of cooling-air and preventing oil from passing out from said passages, substantially as described. 95
2. An oil-container for motors, comprising 100

a main body portion secured to the lower end of the motor-cylinder, the motor crank and pitman being arranged in the said body portion, side inclined passage-ways leading into 5 the said body portion and screens or perforated plates closing each end of the said passages, the structure being such that cooling-air may be permitted to enter the said body portion but the oil which is thrown about by the 10 movement of the crank and pitman, cannot escape from the said passages, the first screen breaking up or stopping the said oil, so that it will not strike the second or outer screen, and the inclined walls of the said passages 15 turning the oil to the body portion again, substantially as described.

3. An oil-retainer for motors comprising a body portion adapted to support the cylinder of the motor and provided with an oil-well in-

teriorly thereof, laterally and upwardly extending passage-ways having inclined walls leading from the said oil-well to the outside atmosphere, inclined screens or perforated plates closing each end of the said passage-ways so that cool air may enter the oil-well 25 but dust will be excluded therefrom, and oil will be prevented from passing out the said passages and will be returned to the well by the inclined sides of the same, substantially as described.

Signed at Brussels, Belgium, this 13th day 30 of July, 1899.

EDOUARD ALEXIS VIVINUS.
AUGUST JULES HECHT.
